GARMENT HANGER

Joseph E. Ericson, Kensington, Conn.

Application April 30, 1946, Serial No. 666,086

1 Claim. (Cl. 223—86)

1

This invention relates to a garment hanger, and more particularly to a coat hanger or the like.

A primary object of this invention is the provision of an improved garment hanger characterized by means whereby moth balls or perfume balls, or the like may be intimately associated with the hanger for the impregnation of the garment, either to perfume the associated garment, or to serve as a moth repellent in conjunction with the article, depending on the type of balls used therewith.

An additional object of the invention is the provision of such a device provided with means whereby balls may be readily positioned therein and removed therefrom as desired.

Still another object of the invention is the provision of such a garment hanger which is sturdy and durable in construction, reliable and efficient in operation, and relatively simple and inexpensive to manufacture, assemble and utilize.

Other objects will in part be obvious and in part be pointed out as the description of the invention proceeds, and shown in the accompanying drawings, wherein there is disclosed a preferred embodiment of this inventive concept.

In the drawings:

Figure 1 is a side elevational view, partially in section, showing one form of garment hanger embodying the instant inventive concept.

Figure 2 is an end elevational view of the device shown in Figure 1.

Figure 3 is a fragmentary sectional view taken substantially along the line 3—3 of Figure 1, as viewed in the direction indicated by the arrows.

Figure 4 is a fragmentary sectional view taken substantially along the line 4—4 of Figure 1, as viewed in the direction indicated by the arrows.

Similar reference characters refer to similar parts throughout the several views of the drawings.

Referring now to the drawings, the garment hanger, generally indicated at 10, includes a wire portion 11 having shoulders 12, from which extend angularly disposed portions 13 terminating in vertical portions 14. The upper horizontal portion 11 has secured thereto in any desired manner a hook-shaped member 15 adapted to support the hanger from a rod in the conventional manner.

The depending vertical portions 14 extend through vertical bores 25 in a tubular transverse member generally indicated at 16, and are turned at their ends, as at 17, in such manner as to support the tubular member 16 in related assembly with the wire portion. The tubular member 16 is provided with an enlarged central aperture 18 of a size adapted to permit the passage therethrough of mothballs 20 or perfume

balls or the like, into the interior of the tubular member 16. The mothballs are adapted to gravitate towards the end of the device, and be held therein by the vertical portions 14 of the member 10. Perforations 21 are provided at suitably spaced intervals along the length of the device to permit the vapor exuded by the balls to impregnate the garment adapted to be suspended from the hanger.

From the foregoing, it will now be seen that there is herein provided an improved garment hanger characterized by a tubular bar member adapted to contain mothballs or the like, wherein the mothballs may be inserted with a minimum of difficulty and effort and removed therefrom for replacement, as may be necessary. It will also be seen that there is herein provided a device which accomplishes all of the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

In a garment hanger, a wire member including a supporting hook and downwardly-diverging portions extending laterally of said hook adapted to provide shoulder-supporting portions for a body garment, said portions terminating in substantially vertical depending extremities, a tubular hanger bar open at both ends and adapted to contain a vapor-disseminating material, said bar being formed to provide a pair of vertically aligned apertures adjacent each end thereof, said vertical extremities of said wire member extending through said apertures to partially close said open ends but providing vapor passages therearound, the free ends of said extremities being upset below said bar and longitudinally thereof to retain said bar thereon, and said bar being formed to provide an opening in the upper surface thereof for the insertion of vapor-disseminating material therein.

JOSEPH E. ERICSON.
